(57) **CLAIM**

The ornamental design for a hearing device, as shown and described.

DESCRIPTION

FIG. 1 is a front elevation view of a hearing device in accordance with the claimed design and shown relative to an ear;

FIG. 2 is a front right perspective view of the design of FIG. 1;

FIG. 3 is a front elevation view of the design of FIG. 1; FIG. 4 is a rear elevation view of the design of FIG. 1; FIG. 5 is a right side elevation view of the design of FIG. 1; FIG. 6 is a left side elevation view of the design of FIG. 1; FIG. 7 is a top plan view of the design of FIG. 1; and, FIG. 8 is a bottom plan view of the design of FIG. 1.

The ornamental design also includes the mirror images of the views illustrated in FIGS. 1-8.

The dash-dash broken lines in the figures represent environment and form no part of the claimed design.

The dot-dash broken lines in the figures immediately adjacent the solid lines represent a boundary between claimed and unclaimed subject matter and form no part of the claimed design.

The labels used herein to describe orientation (e.g., top, bottom, left, right) are merely for reference and are not intended to limit the interpretation of the design.
